DRESSING STAND

William M. Earley, Hagerstown, Md.

Application August 17, 1948, Serial No. 148,152

Term of patent 14 years

(Cl. D33—8)

To all whom it may concern:

Be it known that I, William M. Earley, a citizen of the United States of America, and a resident of the city of Hagerstown, Washington County, State of Maryland, have invented a new, original, and ornamental Design for a Dressing Stand, of which the following is a specification, reference being had to the accompanying drawing, forming a part thereof.

In the drawing,

Fig. 2 is an enlarged perspective view of the upper portion of the stand.

Fig. 3 is a horizontal sectional view on the line 3—3, Fig. 1.

I claim:

The ornamental design for a dressing stand, substantially as shown.

WILLIAM M. EARLEY.
